UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

IRONING-MACHINE.

1,125,968.

Specification of Letters Patent.

Patented Jan. 26, 1915.

Application filed December 6, 1912. Serial No. 735,216.

To all whom it may concern:

Be it known that I, DANIEL M. COOPER, of Rochester, in the county of Monroe and State of New York, have invented certain new and useful Improvements in Ironing-Machines; and I do hereby declare the following to be a full, clear, and exact description of the same, reference being had to the accompanying drawings, forming a part of this specification, and to the reference-numerals marked thereon.

My invention relates to laundry machinery and more particularly to pressing machines of the type embodying a bed and platen one of which parts is movable vertically and laterally with respect to the other, and it has for its object the provision of an improved arrangement for the purpose of locking the operating means which effects vertical movement of the movable part until the latter has completed its lateral movement and is in proper position for the pressing operation.

To this and other ends the invention consists in certain improvements and combinations of parts all as will be more fully described hereinafter, the novel features being pointed out in the claims at the end of the specification.

In the drawings: Figure 1 is a side elevation of a machine embodying a preferred form of the invention, showing the locking means disconnected from the valve operating means; Fig. 2 is a detail elevation of the fluid pressure cylinder and valve and the cooperating parts, the locking device being engaged with the valve operating means; Fig. 3 is a rear end elevation; Fig. 4 is a sectional view on the line 4-4 of Fig. 1; Fig. 5 is a plan view, with parts broken away, and Fig. 6 is a sectional view on the line 6-6 of Fig. 4.

Similar reference numerals throughout the several figures indicate the same parts.

In the present embodiment, the machine comprises a frame 1 and arms 2 at the top thereof which support the posts 3 upon which is mounted a stationary platen 4 that may be supplied with steam or other heating agent in the usual manner in this class of devices. Arranged for vertical movement in the frame is a post 5 which carries the support 6 on which the bed is mounted for lateral sliding movement. For this purpose, the bed embodies a suitable frame 8,

carrying the dovetail slide 9 which engages a corresponding guideway in the support. The post 5 is connected to a toggle joint comprising links 10 and 11, the latter of which is pivoted in the frame at the base 60 thereof, as indicated at 7. The post is operated by a suitable fluid pressure controlled elevating means and to this end, the toggle joint just referred to is suitably connected to a piston traveling in the cylinder 12, to 65 which fluid pressure is admitted from a suitable source of supply, effecting straightening of the toggle joint and consequent raising of the post 5 and the support which carries the bed. The operating means is preferably controlled by a rotary fluid pressure supply valve which is arranged on the shaft 13. The operating means for the valve may comprise a ratchet wheel 14 fixed on the shaft 13 and arranged to be engaged by a 70 spring actuated pawl 15. The pawl 15 is carried on the arm 16 which is journaled on the shaft 13 and carries a leaf spring 17 in engagement with said pawl.

18 is a rod connecting the arm 16 with the upstanding portion 19 arranged upon the pivoted treadle 20. At each operation of the treadle 20, the valve is rotated a quarter of a revolution for opening or closing, and in this way the bed is alternately 80 raised and lowered with respect to the stationary platen. A suitable spring 33 is secured between the portion 19 and a stationary part of the machine, and serves to return the treadle and valve operating means 85 to normal position after each operation.

The chief objection to this type of machine lies in the fact that a careless operator may open the controlling valve before the bed is in its proper position beneath the 90 platen, thus permitting the neckband engaging members to be brought into engagement with the platen, damaging the machine, or otherwise interfering with its operation, and to this end, in the present embodiment, I have provided instrumentalities for positively locking the valve against movement, by a device that is automatically released when the bed is moved laterally to its proper pressing position beneath the 95 platen, the release of the locking device preferably taking place at the limit of the movement of the bed. This may be accomplished in various ways, and preferably I provide a gravity actuated locking device 21 which is 100

pivoted at 22 and offset at 23 whereby to bring the nose 24 into the path of a pin 25, projecting laterally from the pawl 15 far enough to be engaged by the locking device.

5 26 is a connecting rod leading from the locking device 21 to a bell crank lever 27 which is pivoted at 28 upon the bracket 29 and is connected to a trip member, preferably in the form of a slidable arm 30. The 10 arm 30 is supported upon a vertical extension 31, and provided at its free end with an upstanding portion 32 arranged in the path of the bed, and adapted to be engaged by the slide 9 when the bed reaches its innermost position, as shown in Fig. 1. In this 15 position, the sliding arm 30 is moved outwardly, causing the connecting rod 26 to be lifted and thus raising the locking member out of engagement with the valve operating 20 means which may then be actuated to admit fluid pressure to the cylinder. Upon the completion of the pressing operation, the treadle is operated to effect further movement of the valve, thus releasing the fluid 25 pressure from the cylinder, and permitting the support, which carries the movable bed, to fall, after which the bed may be moved laterally upon the support, away from pressing position. Upon moving the bed laterally away from its pressing position beneath the platen, the weight of the locking device causes it to drop into engagement with the pin 25 and prevent further movement of the valve until the bed is returned to its 35 inner position.

I claim as my invention:

1. The combination with a stationary platen, of a vertically movable support, a bed laterally movable on the support, fluid 40 pressure means for elevating the support embodying a valve controlling the admission of fluid pressure, operating means for the valve, and a locking device movable independently of the bed and adapted to engage 45 the operating means, said locking device being controlled by the position of the bed.
2. The combination with a stationary platen, of a bed movable vertically and laterally of the platen, fluid pressure means for 50 elevating the bed embodying a valve controlling the admission of fluid pressure, operating means for the valve, and a locking device movable independently of the bed and adapted to engage the operating means, said locking device being controlled by the position of the bed.
3. The combination with a stationary platen, of a vertically and laterally movable bed, fluid pressure means for elevating the 60 bed, a valve controlling the admission of fluid pressure, operating means for the valve, and a locking device movable independently of the bed, said locking device being normally in engagement with the valve operating means, and connections 65

between the bed and the locking device whereby the latter is moved out of engagement with the valve operating means at the limit of the movement of the bed laterally to pressing position.

4. The combination with a stationary platen, of a vertically and laterally movable bed, fluid pressure means for elevating the bed, a valve controlling the admission of fluid pressure, operating means for the valve, 70 a gravity actuating locking device movable independently of the bed and normally in engagement with the valve operating means, and a trip member connected with the locking device and arranged to be engaged by the bed during its lateral movement to pressing position.

5. The combination with a stationary platen, of a vertically movable support, a bed laterally movable on the support, fluid 85 pressure means for elevating the support, a valve controlling the admission of the fluid pressure, operating means for the valve, a gravity actuated locking device movable independently of the bed and normally in engagement with the valve operating means, a trip member mounted in the path of the bed so as to be engaged by the same at the limit of its lateral movement to pressing position, an angle arm pivoted 90 to said trip member, and a connecting rod leading from said angle arm to the locking device.

6. The combination with a stationary platen, of a bed movable vertically and laterally of the platen, fluid pressure means for elevating the bed embodying a valve, operating means for the valve, and a lock 100 for said operating means movable independently of the bed and arranged to be controlled by the same.

7. The combination with a platen and bed, one having movement vertically and laterally of the other, fluid pressure means for elevating the movable member embodying a valve, and a lock for said valve movable independently of the aforesaid member and arranged to be controlled by the same.

8. The combination with a stationary platen, of a support, one of said members 115 being movable relatively to the other, a bed laterally movable on one of the members, fluid pressure means for effecting engagement between the movable members embodying a valve, operating means for the valve, and a locking device movable independently of said bed and adapted to engage the operating means, said locking device being controlled by the position of the bed.

9. The combination with a platen, of a bed, one movable vertically and laterally relatively to the other, fluid pressure means for effecting engagement between said members, the valve controlling the admission of 120

125

130

fluid pressure, operating means for the valve, and a locking device movable independently of the aforesaid movable member, said locking device being normally in engagement with the valve operating means, and connections between the movable member and the locking device whereby the lat-

ter is moved out of engagement with the valve operating means when the parts are in pressing position.
